UNITED STATES PATENT OFFICE.

FRED BECKER, OF BUFFALO, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed December 13, 1924. Serial No. 755,629.

This invention relates to gaging and holding devices for work-sheets in a typewriting machine, and one of its objects is the provision of means for holding a card 5 or the like in a predetermined position for typing a line near its bottom edge.

A card is inserted, bottom edge first, in front of a typewriter platen and is positioned in a plane tangential to the platen 10 by backing the card against an upstanding table having a guiding edge formed thereon for laterally positioning said card. There is provided a spring-leaf for holding the card against the table, and the ends of the 15 spring are turned up on a bias, forming a throat for introducing the card between the spring and the table. The card is then set up with its leading edge against gages, and the gages serve to position the card for the 20 line of typing.

To assist in positioning and removing the card, the table supporting the card is provided with a concave finger groove which serves to expose a portion of the 25 card at the rear of the leading edge so that an operative may easily place a finger behind the card for manipulating it.

In many cases it is desirable to type a line near the bottom edge of cards having 30 an uneven leading edge, that is to say, a leading edge having a portion cut out forming a step. Locating gages are provided having individual adjustments. For the purpose of supporting the gages there 35 are provided upwardly-extending guiding pieces and gages sliding thereon. The sliding gages may be set to different positions corresponding to the various outlines of the leading edges of the irregular cards.

40 Other features and advantages will hereinafter appear.

In the accompanying drawings,

Figure 1 is a front view in elevation showing the table mounted on the platen 45 frame of a typewriting machine.

Figure 2 is a cross-sectional view in elevation through the line 2—2 of Figure 1, looking in the direction of the arrows.

Figure 3 is a cross-sectional view in a 50 plane through the line 3—3 of Figure 1, showing the spring with the ends bent out.

Figure 4 is a fragmentary front view of the gages positioned for a card, having a portion of its leading edge cut out.

55 Figure 5 is a perspective view, showing

one of the paper-gages and a portion of one of the guides upon which the gages slide.

A card or work-sheet 10, upon which it is desired to type one line near its bottom 60 edge, may be inserted, bottom edge first, in the front side of a platen 11, which is mounted on a shaft 12 and is journaled in side frames 13. The work-sheet is first laterally positioned and trued by means of 65 a turned-up edge 14 which forms an integral part of a table 15. The card is forced downwardly between the ends 16 of a spring 17 and said table, and then pulled upwardly to a position as shown in Figure 70 1, in which the leading edge of the work-sheet is bearing against regulating or locating gages 18. Said gages are slidably mounted on guides 19 which are fastened to the table 15 by means of rivets 20. 75

Having positioned the work-sheet, a line of typing may be printed thereon by striking type-bars 21 against the platen. Then the work-sheet may be removed, a fresh sheet inserted, and a new line typed thereon. 80

In order to assist in inserting and removing the work-sheet, there is provided a groove 22 in the table 15 which extends downwardly from its uppermost edge to a point 23 near the lower edge. This groove 85 is designed to expose a portion of the rear of the leading edge 24, thus enabling the operative to grip the work-sheet conveniently with a finger behind it.

In many cases it is desired to type one 90 line near the bottom edge of cards having an uneven leading edge, that is to say, a leading edge having a portion cut out, as shown in Figure 4, in which a portion of it, indicated by the numeral 25, is higher than 95 other portions, indicated by the numerals 26 and 27, which indicate different steps to which the gages 18 may be adjusted to suit the outline of the cards. The independent adjustability of the two gages of this device enables the operative to use it for cards having either a straight or stepped leading edge, and is a feature which considerably broadens the scope of work to which it may be adapted. 100

For the purpose of attaching this device to a typewriting machine, and in order that the same may be readily detached therefrom, there are provided finger-screws 28 105 which are substituted for the screws normal- 110

ly provided in the machine for holding a guard 29 on the frames 13. Said screws 28 support a bar 30 which is fastened between the screws 28 and a spacing washer 31. The 5 bar 30 is placed parallel to the platen 11 and has fastened thereon, by means of screws 32, the table 15. Depressions 33 are formed in the table 15 for concealing the heads of the screws 32, as shown in Figure 2, in order 10 that the table may form a continuous flat surface. For positioning the table 15 so that its edge 14 may be placed perpendicularly to the platen 11, there are provided elongated slots 34 co-operating with the 15 screws 32, which permit the adjusting of said table.

The gages 18 for positioning the work-sheet comprise a block into which grooves 35 are cut. The guides 19 are designed to 20 enter into the grooves 35, so that the block may be slid along said guides, and the gages 18 are provided with screws 36 for binding the block in any position to suit the outline of the leading edge of the work-sheet, or to 25 suit the position of the line of typing and the size of the sheet.

The spring 17 is fastened to a supporting member or bracket 37 by means of a fastener 38, and the bracket 37 is mounted on the 30 table 15 of which it forms an integral part. As is shown in Figure 3, the bracket 37 is fastened to the table 15 by means of rivets 39, but it is obvious that the same might 35 form a part of said table instead of being a separate bracket fastened thereon. The ends 16 of the spring 17 are bent outwardly and upwardly, so that the lowermost edge of the ends 16 is the only point bearing on the table. The bias at the ends of the spring 40 17 forms a funnel-like throat 40, as shown in Figure 2, for assisting in introducing the work-sheet between the spring and the table.

There are shown in the drawings means 45 for introducing a work-sheet at the introductory side of the platen including a paper-chute 41 and pressure rolls 42 and 43. The platen 11 is operable by means of a finger-wheel 44. These parts are shown to 50 illustrate the relative position of the table which forms the subject of this invention.

The presence in the table 15 of the groove 22, whose wall may be seated in a notch in the bar 30, or be arranged with the same depth as the depressions 33 for engaging 55 against the front edge of the bar, braces the thin one-piece plate or table 15 against being bent out of true by rough handling.

Variations may be resorted to within the 60 scope of the invention, and portions of the improvements may be used without others.

Having thus described my invention, I claim:

1. In a typewriting machine, the combination with a platen-frame and a platen, 65 of an upright table mounted on the deliv-

ery side of said platen, work-piece-holding means on said table, two vertical guide-strips mounted on said table and spaced a short distance forwardly therefrom, gage-blocks having slots for movably engaging 70 about said guide-strips, and means for adjustably holding said gage-blocks on said guide-strips, said slots being arranged for disposing a portion of said blocks below said strips, whereby a work-piece abutted against said blocks cannot slip between them and said guide-strips.

2. In a typewriting machine, the combination with a platen-frame and a platen, of a table supported on said platen-frame for gaging and holding a work-sheet thereon and in typing position against said platen, said table including an upright plate having a forwardly-projecting flange at its left side, two vertical guide-pieces carried by said plate and spaced a short distance forwardly therefrom, a gage-block adjustably fastened on each of said guide-pieces, and a spring arranged for holding the work-sheet against said plate and said platen.

3. In a typewriting machine, the combination with a platen-frame and a platen, of a table supported on said platen-frame for gaging and holding thereon a card having an irregular leading edge in position against said platen for having a line of data quickly typed adjacent its lower edge and parallel thereto, said table including an upright plate having a forwardly-projecting flange at its left side, two vertical guide-pieces carried by said plate and spaced a short distance forwardly therefrom, a gage block adjustably mounted on each of said guide-pieces, a vertical groove in said plate positioned between said guide-pieces for permitting an operative's finger to engage behind a card, and a spring arranged for holding the card against said plate while it is being gaged and thereafter while it is being typed.

4. In a typewriting machine, the combination with a platen, and a platen-frame therefor, of a table at the delivery side of the platen for positioning a work-sheet thereon, said table comprising an angular bend at one of its sides for positioning the work-sheet in letter-spacing direction, means for adjustably mounting said table tangentially to said platen, including a bar fast on the platen-frame upon which the table is mounted, means for resiliently holding said work-sheet flat against said table, including a bow-spring supported at the center by a bracket integral with said table, and said spring having the ends bent, forming an entering bias between said table and the ends of said spring, locating gages for trueing said work-sheet, including two guiding members upon which individual gages are slid thereon, and means for setting said

gages at any position along the guiding members conforming to the outline of the leading edge of said work-sheet, and means for exposing a portion of the leading edge 5 of said work-sheet, including a concave finger-groove extending substantially from the top to the bottom of said table.

5. In a typewriting machine, the combination with a platen-frame and a platen, of 10 a rod detachably mounted on said platen-frame and parallel with said platen, a plate adjustably mounted on said rod, two independently adjustable gages on said plate for gaging the leading edges of a card, and 15 a lateral gage, said plate having a finger-groove in its wall arranged for engaging with said rod for bracing said plate.

6. In a typewriting machine, the combination with a platen-frame and a platen, of 20 an upright plate mounted on said frame at the delivery side of said platen, gages on said plate for positioning a card thereagainst for typing on the latter, and a bow-spring supported above said plate and extending along the bottom edge thereof for 25

holding the card against said plate, said bow-spring having its ends bent slightly forward and twisted so as to form upwardly-opening throats.

7. A work-piece holding device for a 30 paper-table of a typewriting machine, including a bow-spring supported above said table with its ends resting thereupon, said ends being bent to form upwardly-opening V-shaped throats whereby the work-piece 35 may be readily inserted downwardly between said spring and said table.

8. In a typewriting machine, the combination with a platen, of a rod supported 40 above said platen, and a paper-table mounted on said rod substantially tangent to said platen; said table having slotted countersunk mounting portions arranged for engaging against said rod, and a vertical finger-groove extending from near its bottom edge 45 to its top edge, the wall of said groove being arranged for engaging said rod so as to brace said table.

FRED BECKER.
